C. S. FRANKLIN

ELECTRICAL CONDENSER

Filed June 21, 1921

Inventor

CHARLES SAMUEL FRANKLIN.

By his Attorney
W. A. Adams

UNITED STATES PATENT OFFICE.

CHARLES SAMUEL FRANKLIN, OF LONDON, ENGLAND, ASSIGNEE TO RADIO CORPORATION OF AMERICA, A CORPORATION OF DELAWARE.

ELECTRICAL CONDENSER.

Application filed June 21, 1921, Serial No. 479,362, and in Great Britain January 11, 1916.

This invention relates to electrical condensers and is particularly suitable for those in which air or oil is used as the dielectric.

It is well known that with condensers composed of similar flat plates the tendency to break down is greater at the edges than at other parts; consequently such plates cannot be placed at a distance apart less than that which must be allowed between 10 their edges for the potential at which the condenser is required to work.

According to this invention a condenser is formed of a series of overlapping coaxial cones of conducting material each of which 15 has its bottom edge turned out and rounded off into a flange and has its apex rounded and preferably closed or nearly closed. These cones may be suitably supported by their flanges.

20 By this invention the greater portions of the surfaces of the plates may be brought together nearer than their edges and having regard to the effective distance between the plates and the possible working potential an economy of space is effected.

The accompanying drawing is a sectional elevation of four cones arranged as a condenser in accordance with this invention. Each cone has its base turned out so as to 25 form a flange a the edge of which may be rounded off to form a bead b as shown.

It will be obvious that if θ is half the angle at the apex of the cone and α the distance between the cones, then the distance d 30 between the edges of the flanges is $\alpha/\sin \theta$. Practically the angle θ is determined by

considerations of the details of manufacture and of the materials used; the maximum value for θ is, however, determined by experience. Thus, supposing that, for the 40 particular material, dielectric and potential to be used, it is found that the edges require to be twice as far apart as the other portions of the plates, the angle θ must not be more than 30° . 45

The cones may be supported in any convenient manner, the even numbers being connected to one terminal and the odd numbers to the other terminal.

Having described my invention, what I so claim is:

1. A condenser comprising a plurality of nested conical plates of conducting material, variably spaced, the angles between the apexes of the cones and their sides being selectively varied in accordance with the nature of the dielectric used, each plate being provided with a flange extending substantially at right angles to the axis of the cone and having its outer edges rounded off to form a bead. 55

2. In combination, a plurality of nested conical condenser plates of conducting material comprising effective portions and supporting flanges, said plates being so arranged that the perpendicular distance between effective portions of adjacent plates is less than the perpendicular distance between the supporting beaded flanges of adjacent plates. 60
